UNITED STATES PATENT OFFICE

2,190,928

FLARE TORCH

Rudolph Kovac, Chicago, Ill., assignor to American Automatic Devices Co., Chicago, Ill., a corporation of Illinois

Application March 9, 1936, Serial No. 67,974
Renewed April 14, 1938

6 Claims. (Cl. 67—55)

My invention relates to flare torches of the type adapted for use on a highway or the like as a warning signal for approaching vehicles to indicate an obstruction of the way. The laws of a number of the states require the use of flags or their equivalents by day and of lighted torches by night in substantially spaced relation along a highway at opposite sides of a truck broken down on the highway, and require that suitable signal devices be carried by all trucks at all times when travelling on the highway under such conditions as to be immediately available for signal purposes in case of a breakdown. It has been one of the objects of my invention to construct and arrange 5 my improved flare torches so that they shall, without any reasonable possibility of failure, be ready for use for prolonged periods for producing flares capable of being seen readily at considerable distances without at the same time 10 being likely momentarily to blind the driver of an approaching vehicle.

To these ends, it has been the object of my invention to provide an improved burner of such a type that the flame shall be hard to extinguish both when it is freshly lighted and when it has become thoroughly heated in continued use, that the flame or at least the base portion of the flame be protected from rain, that there shall be a liberal feeding of air to the flame and ample opportunity for the flame to escape at the top portion of any protecting housing while at the same time the flame shall be protected at the critical point from the effects of a heavy wind from any side, and that the device shall be fully protected when 15 out of use against loss of fuel by splashing or by evaporation and shall be protected when in use against any loss of fuel by leakage from the saturated wick or by condensation of vaporized fuel on the surface of the burner or associated parts.

It is one of the objects of my invention to provide in my improved arrangement a small drain pan about the wick tube in position to receive any oil dripping from the saturated wick and in position to receive any minute particles of oil falling in the zone immediately surrounding the wick, such drain pan being connected by a small opening with the upper end portion of the oil receptacle so as to permit any oil collecting in the 20 pan to run back into the receptacle, such opening between the pan and the receptacle being adapted also for permitting any gases to escape from the receptacle so as to prevent the establishment of any considerable pressure in the receptacle when it becomes heated. It is one of the objects of

my invention to provide an arrangement in which such pan is incorporated as a part of the framework or supporting means of the burner, this result being attained preferably by the formation of the pan as the body portion of a spider upon 5 the radially extending arms of which is mounted the housing member by which the bottom portion of the flame is protected against wind and against rain and in connection with which the entrance of air for combustion and the escape of the hot 10 gases are more or less completely controlled.

It is one of the objects of my invention to provide an improved form of housing member for controlling the passage of air to the flame and for protecting the flame from the rain and the wind, 15 whereby an ample supply of air may be provided for complete combustion of the fuel and for production of a flame which shall rise a considerable distance above the wick while at the same time the base of the flame is completely protected 20 against cross currents of air by which the flame would be likely to be extinguished. It is one of the objects of my invention to provide an improved arrangement of this type by which air is 25 permitted to pass upwardly through large openings between the wall of the housing member and its central supporting means into the combustion chamber in the housing from which in turn the heated gases are free to pass obliquely upwardly 30 and outwardly with the flame through openings in the side wall of the housing near the top of the housing, said side wall openings being spaced about the housing and being of such size in the aggregate as compared with the inlet openings 35 at the bottom as to prevent the establishment of any substantial back pressure in the combustion chamber.

It is another object of my invention to improve devices of this type in sundry details hereinafter pointed out. The preferred means by which I 40 have accomplished my several objects are illustrated in the drawings and are hereinafter specifically described. That which I believe to be new and desire to cover by Letters Patent is set forth in the claims.

In the drawings,

Fig. 1 is a face view of my improved flare device, with the snuffer cap removed and with a portion of the device broken away at one side;

Fig. 2 is a similar view of the device from the 50 opposite side and with the snuffer cap in position;

Fig. 3 is a central vertical sectional view through my improved device, with certain of the parts showing in side elevation;

Fig. 4 is a central vertical sectional view 55

through the wick tube and its associated mounting and supporting parts;

Figs. 5 and 6 are horizontal sectional views taken respectively at line 5—5 and line 6—6 of Fig. 4;

Fig. 7 is a vertical sectional view taken at line 7—7 of Fig. 5, but showing also the combustion chamber housing and portions of the wick and the oil receptacle;

Fig. 8 is a horizontal sectional view taken substantially at line 8—8 of Fig. 7 but with the wick removed, and with parts broken away at one side of the wick tube and associated parts for clearness of illustration; and

Fig. 9 is an enlarged detail view, being a section taken at line 9—9 of Fig. 8.

Referring now to the several figures of the drawings, in which corresponding parts are indicated by the same reference characters 20 indicates a receptacle which in the arrangement shown is formed of sheet metal having an upwardly extending neck portion 21, at the top of which the metal is turned inwardly to provide an inwardly extending flange 22 at the inner edge of which is provided a downwardly extending flange 23 in the form of locking lugs as is usual in connection with gas tanks of automobiles, for example. At a point just outside of the neck 21 I have provided an annular rib 24 adapted to form a seat for a gasket 25 carried by a metal cap 26 which is secured in position by means of outwardly extending arms 27 on the cap engaging with the horizontal arms 28 of brackets 29 extending upwardly from the receptacle 20, the arrangement being such that the gasket 25 is compressed so as to insure a tight closure between the cap 26 and the receptacle 20. In the arrangement shown, the cap 26 is connected with the receptacle 20 by means of a chain 30 so as to insure that the cap shall be always available for use for a tight closure of the opening through the neck 21.

The burner of my improved device comprises a wick tube 31 (see Fig. 4) which extends 45 through a central opening in a spider member comprising a sleeve 32 and outwardly extending arms 33, 34 and 35. In the arrangement shown, the body portion of the spider upon which the sleeve 32 and the outwardly extending arms are 50 mounted is in the form of a pan 35a as is clearly shown in said Fig. 4. The sleeve portion 32 of the spider is pressed outwardly at one side as is best shown in Fig. 8 to provide a longitudinally 55 extending groove 36 in the inner face of the sleeve arranged so as to provide a vent through the sleeve alongside of the wick tube 31.

For mounting the spider and the wick tube in position upon the receptacle 20, I have provided a closure plate 37 having a downwardly extending flange 38 thereabout at its outer edge with a gasket 39 inside of the circular flange 38 adjacent to said plate 37. The closure plate 37 is provided with a central opening by which it is mounted upon the sleeve portion 32 of the spider adjacent to the bottom of the pan 35a. A metal ring 40 is also mounted upon the sleeve 32 inside of the gasket 39, the closure plate and the ring 40 being rigidly secured in position upon the sleeve 32 of the spider member by means of a turned lower end portion 41 of the sleeve. As is clearly shown in Fig. 8, the plate 37 is provided with a notch at one side to receive the rib of the sleeve 32 formed in connection with the groove 36, the ring 40 being similarly notched, whereby the ring 40 and the closure plate 37 are both held securely against

rotary movement with respect to the sleeve 32 and the spider. As is clearly shown in Fig. 4, the ring 40 is provided at opposite sides with downwardly extending arms 42 which at their lower ends are provided with outwardly extending portions 43. The arrangement is such that the gasket 39 is in position to engage the outer edge portion of the inwardly turned flange 22 of the neck portion of the receptacle 20, as is clearly shown in Fig. 7, the outwardly extending arm 10 portions 43 being in position to engage the lower faces of the cam portions 23 for locking the closure plate 37 and its associated parts in position upon the receptacle. In the arrangement as shown in Fig. 7 and as above described, it will be 15 appreciated that the groove 36 serves as a vent continuously open from the interior of the receptacle 20 to the upper face of the spider member comprising the pan 35a.

As is best shown in Fig. 4, the outer end portion 44 of each of the spider arms 33, 34 and 35 is turned downwardly and is provided in its end face with a notch 45 centrally thereof. Upon such arms 33, 34 and 35 I have mounted a housing 47 formed of sheet metal with a top portion 48 formed integrally therewith, the lower end portion 49 of the housing being offset outwardly by the provision of an outwardly extending flange portion 50 providing a downwardly facing shoulder in the housing adapted to seat against the 30 arms with the offset portion 49 fitting snugly about the downwardly turned end portions 44 of the arms. As is best shown in Figs. 7 and 9, the lower edge of the outwardly offset portion 49 of the housing is crimped inwardly into gripping engagement with the notches 45 in the end faces of the arms for holding the housing rigidly in position upon the arms of the spider. As will be appreciated from an inspection of Figs. 7 and 8, the housing 47 is held in outwardly spaced relation to the body portion 35a of the spider whereby comparatively large openings are provided between the arms for the entrance of air between the pan 35a and the housing member 47. At its upper end portion, the housing 47 is provided with 45 a plurality of outlet openings 51 for the escape of the flame and the heated gases as hereinafter described, the openings 51 being a substantial distance above the upper end of the wick tube 31 and the wick 52 therein. The upper ends of the 50 openings 51 extend substantially to the upper end of the housing.

As is clearly indicated by the arrows in Fig. 7, the air entering between the body of the spider and the lower end portion of the housing 47 is 55 adapted to pass directly upwardly to the openings 51, such openings being arranged in circumferentially spaced relation with respect to the arms 33, 34 and 35, as is clearly shown in Fig. 8. The housing 47 provides complete protection 60 against the entrance of rain except as it may be driven in obliquely, and the housing affords complete protection against the entrance of the wind from any direction directly to the bottom portion of the flame. By the provision of the large openings between the spider arms at the bottom of the housing an ample supply of air for combustion is insured at all times, and the provision of the large outlet openings 51 at the top and the location of such openings closely adjacent to 70 the top wall 48 of the housing assure that there shall be very little if any tendency for the establishment of a pressure condition within the housing 47.

In the arrangement shown, the openings be- 75

tween the spider arms for the entrance of air to the combustion chamber are approximately two and one-half times as large in the aggregate as the inside cross sectional size of the wick tube. 5 In this arrangement, the six openings 51 have an aggregate size approximately four times as great as the inside cross sectional size of the wick tube.

With the receptacle 20 filled with kerosene to 10 a point fairly close to the top, and with the wick 52 in position as shown in Fig. 7 and the cap 26 and the burner comprising the housing 47 in position as shown in Fig. 3, the device as a whole is adapted to stand in stable position on a highway. 15 For use in the daytime, a suitable flag is mounted in position on the receptacle as a base, the staff 53 of such flag being shown in Fig. 2 seated within a vertical socket provided by a sheath 54 along one side of the cap 26.

For use at night, the cap 26 is removed and 20 permitted to hang on the chain 30 so as to be available when desired. With the cap 26 removed, easy access is provided for lighting the wick 52 through one of the outlet openings 51 of the housing, the air necessary for combustion being admitted through the openings between the spider arms and the flame and heated gases being permitted to escape through the openings 51 from the combustion chamber inside of the housing 47, the flame being adapted to rise a substantial distance above the top of the housing so as to be visible from a considerable distance. With the 25 burner lighted, the metal parts of my improved device as shown become gradually heated by direct contact with the flame or by conduction from other parts which do have contact with the flame, as is common in all burners in which the flame is enclosed more or less completely by a metal housing. See for example prior patent to Thomas and 30 Gorton, No. 558,533, of April 21, 1896. Finally the supply of oil in the receptacle becomes heated more or less so as to encourage combustion. In case any of the oil should become vaporized within the receptacle 20 by such heat, any pressure resulting from such vaporization of the fuel inside of the receptacle is relieved and kept to a minimum by reason of the provision of the vent opening through the groove 36. In case any oil should drip from the saturated wick 52, such oil would 35 be caught by the pan 35a from which it would run back into the receptacle 20 through the vent opening 36 or would at least be kept from spreading over the surface of the device.

It will also be appreciated that as the temperature of the receptacle 20 rises through a prolonged period of use, the fuel and the air in the receptacle are both caused to expand so as to force out through the opening 36 a portion of the air. When after a period of use air is forced back into the receptacle through said opening 36 as the parts are cooled, such air will have a tendency to carry with it any oil that may have accumulated in the pan about the opening.

As will be appreciated from a study of my improved device, and particularly from the showing of Fig. 7, the air has a free sweep upwardly through the combustion chamber from the openings between the spider arms to the outlet openings 51 at the top of the housing. Under these conditions, when oil vapor is condensed within the housing so as to cause small drops of the oil to fall, such drops are deflected inwardly by the air so as to fall on the wick or within the pan 35a. I have found in extensive use of my improved

device that substantially all of the fuel is consumed within the combustion chamber, as is shown by the fact that in the use of my device there is practically no collection of fuel on the outer outside surface of the receptacle and practically no deposit of carbon in or about the housing 47. For assuring these results, I have made ample provision for the entrance of air for combustion and have maintained a suitable ratio between the entrance and the outlet openings so as 10 to insure proper mixing of the fuel and air and the proper burning of such mixture.

By the use of my improved arrangement, I am enabled to produce my device very readily and cheaply. The spider, the closure plate 37, the 15 ring 40 and the gasket 39 are preferably first secured together with the end of the sleeve 32 turned outwardly into locking position at 41.

The wick tube 31 is then forced into position in the sleeve 32 where it is held securely by friction 20 for supporting the wick 52 in operative position, the end portions of the wick tube being then flared outwardly from their normal straight condition to the condition as shown in the drawings. The housing member 47 is crimped at the necessary 25 points for holding it securely in place on the spider arms. All of this assembly work is performed very quickly and easily and the structure when completed is highly effective.

By the provision of the cap 26 adapted to be 30 locked to the receptacle 20, my device is fully protected against any loss of fuel by splashing or by evaporation during months or even years of transportation on a truck following the preparation of the device for use. The device is thus 35 definitely assured of being in condition for use when necessary. In the same way, the device is protected against any possibility of contaminating any of the goods being carried by the truck either 40 by direct leakage of the fuel thereon or by evaporation of fuel in the neighborhood of the goods in such manner as to give the goods an objectionable odor. In this way the truck and the goods carried by the truck are also protected 45 against a possible fire hazard since the fuel is definitely confined within the receptacle 20 or at least within the receptacle 20 and the cap 26. The cap 26 is arranged to be used readily for snuffing the flame when desired by shutting off 50 completely the access of air to the burner.

As is clearly shown in Fig. 7, the wick 52 is of substantially greater size than that of the wick tube 31, with the result that the wick is considerably compressed within the tube. As a result of this arrangement, the wick and fuel consumption are kept to a minimum, the compressed wick being much less effective than a loosely mounted wick for drawing the oil upwardly by capillary attraction. This is made possible without danger of the flame's being extinguished by reason of the improved arrangement of my housing by which the flame is protected from air currents directly across the housing.

While I prefer to employ the form of device as shown in my drawings, it is to be understood that my invention is not limited to such arrangement except so far as the scope of the invention may be so limited in terms in the narrower claims.

I claim:

1. In a flare torch, the combination of a spider 70 member comprising a body portion and a plurality of arms extending outwardly therefrom, a wick tube secured in an opening in said body portion, a housing member closed at the top and having a plurality of openings in its side walls 75
